W. H. BENDER NAGEL

TELEPHONE TRANSMISSION SYSTEM

Filed Dec. 22, 1919

Inventor:
William H. Bender Nagel.
by C. P. Soper Atty.

UNITED STATES PATENT OFFICE.

WILLIAM H. BENDERNAGEL, OF QUEENS, NEW YORK, ASSIGNOR TO WESTERN ELECTRIC COMPANY, INCORPORATED, OF NEW YORK, N. Y., A CORPORATION OF NEW YORK.

TELEPHONE TRANSMISSION SYSTEM.

Application filed December 22, 1919. Serial No. 346,584.

To all whom it may concern:

- Be it known that I, WILLIAM H. BENDERNAGEL, a citizen of the United States, residing at Queens, in the county of Queens, 5 State of New York, have invented certain new and useful Improvements in Telephone Transmission Systems, of which the following is a full, clear, concise, and exact description.
- 10 This invention relates to telephone transmission systems and more particularly to such systems in which repeaters are employed. The object of the invention is to improve transmission over trunks connecting operators' positions by including in such trunks amplifying apparatus without disturbing the normal function of the usual signaling arrangements, which provide for supervision of the call by other operators.
- 15 One of the features of the invention is to employ an amplifying repeater in an incoming trunk circuit of a telephone system. Another feature is to render the repeater operative only when connection is established and when ringing current is not being applied. Another feature is to provide signals for the operators and to use the trunk signal relay to indicate that the trunk has been taken for use and to render the amplifier operative. Another feature is to provide an incoming trunk circuit with apparatus for ringing around the repeater. Another feature is to supply talking current from the link circuit to one subscriber and 20 from the trunk circuit to another subscriber. Other features and advantages of the invention will be obvious as the description proceeds.
- The invention will be understood from 40 the description in connection with the drawings in which two embodiments of the invention are illustrated.
- In the drawings, Fig. 1 shows a trunk circuit in which is employed two one-way amplifiers in an incoming trunk circuit which is provided with apparatus for preventing ringing current from going through the repeaters and with apparatus for controlling the supervisory signals.
- 45 Fig. 2 shows two one-way amplifiers in a trunk circuit provided with apparatus for ringing around the repeater and with apparatus for controlling the signals.
- In Fig. 1 reference character A represents 50 an operator's cord or link circuit provided
- with the usual equipment. X and Y represent operators' positions at the respective ends of a trunk circuit. Upon receiving a call for a station, such as B, accessible at position Y, the operator at X inserts her plug P into the jack J of the trunk circuit, which the operator at Y has assigned for that purpose, thereby closing circuit from ground, battery, lamp L, sleeve contacts of plug P and jack J, to ground, thereby lighting the lamp L. Plugging in P simultaneously closes a circuit from battery of the cord circuit through the tip contacts of plug P and jack J, upper half of primary of transformer T, high and low resistance windings of relay 4, which are in series, lower half of primary winding of transformer T, through ring contacts of plug and jack, relay 5, to battery. The relay 4 thereupon operates and closes its alternate contact, thereby lighting the signal lamp L' of operator Y.
- 55 Upon receiving the signal, operator Y plugs plug P' into jack J', thereby closing a circuit from ground, battery, relay 2, sleeve contacts of plug P' and jack J', to ground. The relay 2, upon energization, closes at its left-hand contact a circuit through the filaments of the amplifiers R and R' from ground, battery, left-hand contact of relay 2, contact k and filaments in series to ground. At its right-hand armature relay 2 opens the original energizing circuit for lamp L' and transfers the control of this lamp to the back contact of relay 4.
- 60 Operator Y then operates her ringing key K, thereby ringing subscriber B in the usual way and simultaneously cutting off current from the filaments of repeaters R and R' by opening contact k.
- 65 When the ringing key K is released and subscriber B removes his telephone hook, a circuit is established from ground, through battery, relay 3, lower half of secondary of transformer T, ring contacts of plug P' and jack J', subscriber's set, tip contacts of jack J' and plug P', through upper half of winding of transformer T' to ground. This energizes relay 3, thereby closing its contact which short-circuits the high resistance winding of relay 4. This permits an increased current to flow from battery, through relay 5, and the circuit already traced, thereby maintaining relay 4 energized and operating relay 5, which at its armature and con-

tact short-circuits lamp L_1 . It is thus seen that the insertion of plug P in jack J lights the lamps L and L' ; that insertion of plug P' in jack J' extinguishes lamp L' ; and that removal of receiver from the hook of subscriber B extinguishes lamp L when key K is not in ringing position.

The connection is now in condition for amplifying talking current as follows: Talking current coming through cord circuit A , plug P , jack J , circulates through the primary of transformer T , where it is transferred to the secondary of transformer T and circulates in the circuit including the network N . From this circuit it is transformed to the secondary of transformer T' where it goes to the input side of repeater R and is amplified and goes through the output circuit of repeater R through the circuit including the primary of transformer T' . Here it is transformed to the secondary of transformer T' , and passes through plug P' and jack J' to the telephone of subscriber B . In a similar way talking current from subscriber B is amplified as it passes in the opposite direction except that it is sent through the repeater R' in a manner similar to the way that talking current in the opposite direction is sent through repeater R . When subscriber B hangs up his receiver, the relay 3 is deenergized, thus removing the shunt from the high resistance winding of relay 4 and thereby increasing the resistance of the circuit which has been traced for relay 5 to such an extent that relay 5 is deenergized and lamp L lighted, which now serves as a disconnect signal for operator X . Withdrawal of plug P releases relay 4 , which closes at its normal contact a circuit for the lamp L' , which now serves as a disconnect signal for the operator at Y who removes plug P' from jack J' , thereby releasing relay 2 . The release of relay 2 breaks the circuit of the filaments of the amplifiers and all apparatus is restored to normal condition.

The dotted line m, m serves to distinguish the apparatus individual to the two operators' positions, since all the apparatus located on one side belongs to the operator's position X and all the apparatus on the other side of this line is located at the operator's position Y .

Parts in Fig. 2, which are similar to those in Fig. 1, are designated by the same reference characters except that the subscript 2 is used. The embodiment shown in Fig. 2 is also provided with signal connections and with means for applying ringing current at either end of the trunk circuit without sending it through the repeaters. When the operator at X_2 inserts the plug P_2 in jack J_2 , a circuit is closed from ground, battery, relay 9 , sleeve contacts of plug P_2 and jack J_2 to ground. This closes the contact of relay 9 , but as the contact of relay 10 is open, the

lamp L_2 is not lighted. The insertion of plug P_2 in jack J_2 also closes a circuit through relay 6 as follows: ground, battery, left-hand winding of relay 6 , outer left-hand back contact of relay 7 , lower half of the primary of transformer T_2 , ring contacts of jack J_2 and plug P_2 , relay 10 , tip contacts of plug and jack, upper half of primary winding of transformer T_2 , inner left-hand back contact of relay 7 , right-hand winding of relay 6 to ground. This energizes relay 10 , thereby closing its contact and lighting lamp L_2 . The energization of relay 6 closes its contact, thereby closing a circuit from ground, front contact of relay 6 , right-hand winding of marginal relay 7 , lamp L'_2 , right-hand back contact of relay 2_2 , battery, to ground, thereby lighting lamp L'_2 . Since relay 7 is a marginal relay, the current through its right-hand coil does not close its contacts.

Upon receiving the signal, operator at Y_2 inserts plug P'_2 in jack J'_2 , thereby establishing a circuit from ground through battery, relay 2_2 , sleeve contacts of plug P'_2 and jack J'_2 , to ground.

The relay 2_2 , upon energization, opens the circuit through lamp L'_2 , and also closes its left-hand contact, thereby rendering the repeaters R_2 and R'_2 operative by means of current from ground through battery, left-hand contact of relay 2_2 , key k_2 , filaments of R'_2 and R_2 in series, to ground.

The application of ringing current to subscriber B_2 may be done by operating key K_2 or by operating key K'_2 . If key K_2 is operated, ringing current is sent through the circuit of B_2 in a manner similar to that described above in connection with Fig. 1. If key K'_2 is operated, ringing current is sent through plug P_2 and jack J_2 to the condenser between the two windings of the primary of transformers T_2 , from whence it goes through the relay 8 , thereby closing its contact and energizing relay 11 , which operates key K_2 , thereby applying ringing current to the circuit of subscriber B_2 in the manner already described.

When the subscriber B_2 removes his telephone hook, the relay 3_2 is energized by current from ground through battery, relay 3_2 , lower half of the winding of transformer T_2 , plug P'_2 and jack J'_2 , subscriber's set, to the upper half of the winding of transformer T_2 to ground. The relay 3_2 , upon energization, closes a circuit from ground through contact of relay 3_2 , left-hand winding of relay 7 , battery, to ground. This energizes relay 7 sufficiently to pull over its armature, thereby breaking the circuit which has already been traced through relay 10 and closing a circuit from ground through battery, left-hand winding of relay 6 , forward contact of left-hand outer contact of relay 7 , to ground. The breaking of the circuit

through relay 10 opens its contact, thereby extinguishing lamp L_2 .

It is thus seen that the insertion of plug P_2 in jack J_2 lights the lamps L_2 and L'_2 ; that the insertion of plug P'_2 in jack J'_2 extinguishes the lamp L'_2 and renders the filaments operative; and that the removal of the hook of subscriber B_2 extinguishes lamp L_2 .

10 The amplification of the talking current is not described in connection with Fig. 2 since it is identical with that described in connection with Fig. 1.

Replacing the receiver of subscriber B_2 , 15 breaks the circuit already traced through relay 3_2 , thereby opening its contact and de-energizing relay 7 and closing its left-hand back contacts, which re-establishes current through relay 10, thereby closing the contact of relay 10 and lighting light L_2 to give the operator X_2 the disconnect signal if her plug P_2 is still in jack J_2 . The withdrawal of plug P_2 from jack J_2 deenergizes relay 6, thereby closing a circuit from ground, left-hand back contact of relay 6, right-hand front contact of relay 2_2 , lamp L'_2 , battery, to ground, thus lighting lamp L'_2 to give the operator at Y_2 the disconnect signal. The withdrawal of plug P'_2 from jack J'_2 de-energizes relay 2_2 , thereby opening its left-hand contact to render repeaters R_2 and R'_2 inoperative and all apparatus is restored to normal condition.

What is claimed is:

35 1. In a telephone exchange system, a trunk circuit, a subscriber's line circuit adapted to be connected to one end of said trunk circuit, an operator's link circuit adapted to be connected to the other end of said trunk circuit, an amplifier in said trunk circuit, and means for applying ringing current to said line circuit and simultaneously rendering said amplifier inoperative.

2. In a telephone exchange system, an 45 interoffice trunk circuit, a subscriber's line circuit adapted to be connected to one end of said trunk circuit, an operator's link circuit adapted to be connected to the other end of said trunk circuit, an amplifier in said trunk circuit, supervisory signals, and means for controlling said supervisory signals and rendering said amplifier inoperative.

3. In a telephone exchange system, an 55 incoming trunk circuit, a subscriber's line circuit adapted to be connected to one end of said trunk circuit, an operator's link circuit adapted to be connected to the other end of said trunk circuit, an amplifier in said trunk circuit, means at the outgoing end of said trunk circuit for rendering said amplifier operative, and means for applying ringing current to said line circuit and simultaneously rendering said amplifier inoperative.

4. In a telephone exchange system, an interoffice trunk circuit, a subscriber's line circuit adapted to be connected to one end of said trunk circuit, an operator's link circuit adapted to be connected to the other end of said trunk circuit, an amplifier in said trunk circuit, and means for indicating at one end of said trunk circuit that said trunk circuit has been taken for use and for rendering said amplifier operative.

5. In a telephone exchange system, two operators' positions, a trunk circuit there-between, a link circuit at one of said operators' positions adapted to be connected to said trunk circuit for connecting a subscriber's line to said trunk circuit, a second subscriber's line adapted to be connected to said trunk circuit at the second operator's position, an amplifier in said trunk circuit inoperative when said trunk circuit is idle, a signaling device, a solenoid at said second operator's position for controlling said device, connections to said solenoid responsive while said amplifier is inoperative to the connection of said link circuit to said trunk circuit whereby the operator at the second position is signalled.

6. In a telephone exchange system, two operators' positions, a trunk circuit there-between, a link circuit at one of said operators' positions adapted to be connected to said trunk circuit for connecting a subscriber's line to said trunk circuit, a second subscriber's line adapted to be connected to said trunk circuit at the second operator's position, an amplifier in said trunk circuit, a signaling device, a solenoid at said second operator's position for controlling said device, and means responsive to the connection of said link circuit to said trunk circuit for controlling said solenoid independently 100 of the condition of energization of said amplifier.

7. In a telephone exchange system, two operators' positions, a trunk circuit there-between, a link circuit at one of said operators' positions adapted to be connected to said trunk circuit for connecting a subscriber's line to said trunk circuit, a second subscriber's line adapted to be connected to said trunk circuit at the second operator's position, an amplifier in said trunk circuit, a ringing key at the second operator's position, and an additional contact on said ringing key controlling a condition of said 110 amplifier to render said amplifier inoperative when ringing current is applied to said last mentioned subscriber's line.

8. In a telephone exchange system, two operators' positions, a trunk circuit there-between, a link circuit at one of said operators' positions adapted to be connected to said trunk circuit for connecting a subscriber's line to said trunk circuit, a second subscriber's line adapted to be connected to 120 125 130

said trunk circuit at the second operator's position, a two-way amplifier in said trunk circuit, and means responsive to the answering of the subscriber for the subscriber's line connected at the second operator's position to signal the operator at the first position independently of the condition of energization of said amplifier.

9. In a telephone exchange system, two operators' positions, a trunk circuit therebetween, a link circuit at one of said operators' positions adapted to be connected to said trunk circuit for connecting a subscriber's line to said trunk circuit, a second subscriber's line adapted to be connected to said trunk circuit at the second operator's position, a two-way amplifier in said trunk circuit, a relay at the second operator's position responsive independently of the condition of said amplifier to the answering of the subscriber connected to the trunk circuit at the second operator's position, said relay being connected to that side of said amplifier adjacent said second operator's position, and contacts controlled by said relay for signaling the operator at the first position.

10. In a telephone exchange system, two operators' positions, a trunk circuit therebetween, a link circuit at one of said operators' positions adapted to be connected to said trunk circuit for connecting a subscriber's line to said trunk circuit, a second subscriber's line adapted to be connected to said trunk circuit at the second operator's position, a two-way amplifier having input and output terminals permanently connected in said trunk circuit, a signalling device at the second operator's device controlled by the connection of said link circuit to said trunk circuit independently of the condition of said amplifier, and means responsive to the connection of the subscriber's line at the second operator's position to the trunk circuit for rendering said amplifier operative and for changing the control connections of said device.

11. In a telephone exchange system, two operators' positions, a trunk circuit therebetween, a link circuit at one of said operators' positions adapted to be connected to said trunk circuit for connecting a sub-

scriber's line to said trunk circuit, a second subscriber's line adapted to be connected to said trunk circuit at the second operator's position, a two-way amplifier having input and output terminals permanently connected in said trunk circuit, a ringing key in said link circuit for signalling the subscriber for the subscriber's line connected to the trunk circuit at the second operator's position independently of the condition of energization of said amplifier.

12. In a telephone exchange system, two operators' positions, a trunk circuit therebetween, a link circuit at one of said operators' positions adapted to be connected to said trunk circuit for connecting a subscriber's line to said trunk circuit, a second subscriber's line adapted to be connected to said trunk circuit at the second operator's position, a two-way amplifier in said trunk circuit, a source of signalling current at the second operator's position for signalling the subscriber for transmitting signalling current over the subscriber's line terminating at said second operator's position, and means in said link circuit for controlling the connection of said source to said line independently of the condition of energization of said amplifier.

13. In a telephone exchange system, two operators' positions, a trunk circuit therebetween, a link circuit at one of said operators' positions adapted to be connected to said trunk circuit for connecting a subscriber's line to said trunk circuit, a second subscriber's line adapted to be connected to said trunk circuit at the second operator's position, a two-way amplifier in said trunk circuit, a source of signalling current at the second operator's position for signalling the subscriber for transmitting signalling current over the subscriber's line terminating at said second operator's position, and means in said link circuit for controlling the connection of said source to said line and for simultaneously rendering said amplifier inoperative.

In witness whereof, I hereunto subscribe my name this 19th day of December, A. D. 1919.

WILLIAM H. BENDER NAGEL.
